BUTTON ATTACHER

Bernard R. Lavitch, Encino, and Bernard H. Morry,
Westlake Village, Calif., assignors to Products Interna-
tional Co., Compton, Calif.

Filed Dec. 11, 1972, Ser. No. 313,962

Term of patent 14 years

Int. Cl. D6—99

U.S. Cl. D3—19 A

FIG. 1.

FIG. 2.

FIG. 3.

FIG. 4.

FIG. 5.

FIG. 6.

FIG. 7.

FIG. 8.

FIG. 9.

FIG. 10.

FIG. 1 is a top plan view of a button attacher showing our new design;

FIG. 2 is a side elevational view thereof taken in the direction of the arrow 2 on FIG. 1;

FIG. 3 is a bottom plan view taken in the direction of arrow 3 on FIG. 1;

FIG. 4 is a front end view taken in the direction of arrow 4 on FIG. 2;

FIG. 5 is a rear end view taken in the direction of arrow 5 on FIG. 2;

FIG. 6 is a top plan view of a second embodiment of the design of FIG. 1;

FIG. 7 is a side elevational view thereof taken in the direction of arrow 7 on FIG. 6;

FIG. 8 is a bottom plan view taken in the direction of arrow 8 on FIG. 7;

FIG. 9 is an end view taken in the direction of arrow 9 on FIG. 7; and

FIG. 10 is an end view taken in the direction of arrow 10 on FIG. 7.

We claim:

The ornamental design for a button attacher, substantially as shown and described.
